UNITED STATES PATENT OFFICE

122,118

DESIGN FOR A COMBINED ICE CREAM FREEZER AND DISPENSER

Matthew W. Huber, Chicago, Ill., assignor to
Tuthill Pump Company, Chicago, Ill., a corpora-
tion of Illinois

Application May 6, 1940, Serial No. 92,181

Term of patent 7 years

To all whom it may concern:

Be it known that I, Matthew W. Huber, a citizen of the United States of America, residing at Chicago, in the county of Cook and State of Illinois, have invented a new, original, and ornamental Design for a Combined Ice Cream Freezer and Dispenser, of which the following is a specification, reference being had to the accompanying drawing, forming a part thereof.

Figure 1 is a front view in perspective of a

combined ice cream freezer and dispenser, showing my new design; and

Figure 2 is a rear elevational view thereof, on a slightly reduced scale.

I claim:

The ornamental design for a combined ice cream freezer and dispenser, substantially as shown.

MATTHEW W. HUBER.
